UNITED STATES PATENT OFFICE.

SAMUEL SEGAL, OF NEW YORK, N. Y., ASSIGNOR TO SEGAL LOCK & HARDWARE CO. INC., OF NEW YORK, N. Y., A CORPORATION OF NEW YORK.

SASH FASTENER.

Application filed September 4, 1924. Serial No. 735,727.

My invention relates to improvements in window sash fasteners, its principal object being the production of sash fasteners of this character which shall be simple and inexpensive to manufacture and which shall effectively operate to prevent the opening of the sashes beyond a predetermined distance.

Other and further objects and advantages 10 will appear from the accompanying description, the invention consisting in the novel sash lock and parts thereof hereinafter more particularly described and then specified in the claims.

15 In the accompanying drawing illustrating a practical embodiment of the invention:

Fig. 1 is a front elevation of a fragmentary portion of two slidable window sashes showing the invention applied thereto.

20 Fig. 2 is a vertical section on the line 2—2 of Fig. 1.

Fig. 3 is a horizontal section on the line 3—3 of Fig. 1.

25 Fig. 4 is a sectional view taken through a portion of the device but showing a modification.

Fig. 5 is a plan view of a part of the mechanism of Fig. 4.

30 Fig. 6 is a key for operating the mechanism of Fig. 4.

Referring in detail to the several figures of the drawing and particularly Figs. 1 to 3, inclusive:

35 1 indicates a side rail and 2 the lower rail of an upper window sash, the window pane thereof being indicated at 3. The window pane of the lower window sash is indicated at 4 while the upper rail and a side rail thereof are indicated respectively at 5 and 6. The said window sashes are both slidable towards and away from each other in suitable channels or guideways in a window frame.

40 Secured to the side rail 1 of the upper sash by suitable screws 7 is a plate 8 provided with upper and lower laterally and inwardly extending brackets 9 receiving and supporting a vertical rod 10, substantially squared as shown and provided with sharp corners. 11 indicates a fastening member provided with a screw-threaded opening through which a screw-threaded shaft 12 is threaded, the inner end of said shaft being provided with a head 13 which is recessed as at 13' which recess receives the end

of a spring 14 bearing against the rod 10. A winged nut 15 or other actuator is also threaded over the outer end of the shaft 12. 16 indicates arms preferably integral with the locking member 11, said arms being each provided with a round opening slidably receiving the rod 10. A U-piece 17 is also provided having an opening slidably receiving the shaft 12 as shown in Fig. 3, the head 13 of said shaft acting to prevent removal 60 of said U-piece when the parts are assembled. The legs 18 of said U-piece are each provided with round openings slidably receiving the rod 10.

The device described permits the sashes or either of them to be opened and locked against further opening a distance limited by the length of the rod 10, the lower one being shown partially opened in Figs. 1 and 2 with the lower portion or base of the fastening member 11 engaging the upper rail 5 of the lower sash. If the winged nut 15 has then been tightened the upper sash may then not be lowered or the lower sash raised until the nut has been loosened and the device 70 swung around on the rod 10 into the position shown in dotted lines in Fig. 3.

75 When the winged nut 15 is tightened a double clamping action in two directions is effected. The tightening of the nut presses the member 11 forwardly and jams the edges of the rod 10 against the walls of the round openings in the arms 16. It also causes the head 13 to pull the U-shaped piece 17 rearwardly whereby the edges of the rod 10 are jammed against the walls of the round openings in the legs 18. When the device is not in use and the nut 15 is loose the spring 14 acts to prevent the device from swinging or swivelling on the rod 10. It will be noted 80 furthermore that the plate 8 acts as a stop to prevent the fastening member 11 from being swung around in one direction further than operative position or the position shown in Fig. 1 as the arms 16 will then engage the edge of the plate and also prevents a movement further than that of operative position and in the other direction as the ends of the arms 16 will then engage the rear face of the inner side of the plate. In 85 other words the plate itself prevents the fastening member from being swung through an arc of more than 90°.

90 In the modification of Figs. 4 to 6 inclusive I dispense with the winged nut and pro-

vide the fastening member with an opening 19 receiving the shaft 12 which in this case is not threaded but which is provided with a threaded stem 20 extending through the fastening member and projecting into a larger round opening 21 in the end of the fastening member. This stem has threaded thereon a round member 22 which is rotatably received within the opening 21 and which is provided with a central threaded opening and with slots 23 therein. As is obvious, the member 22 acts as a nut and rotation of the same on the threaded stem will effect the same results as in the preferred form 15 of the invention. To rotate it, however, I have provided a special form of key 24 having fork members 25 adapted to enter the slots 23 of the nut 22 and being also provided with an intermediate slot or opening 25 20 adapted to receive the stem 20 when the nut is rotated in a direction to draw the stem outwardly.

It will be understood to be within the scope of my invention in some cases to make the rod 10 round and to form the openings in the arms 16 and legs 18 squared or other than round. It will also be understood that in some cases I may attach the plate 8 to the window frame and have the device effective as respects one sash only.

What I claim as my invention is:

1. In a device of the character described, a support carried by a member and provided with a sharp edge, a fastening device having an opening provided with a rounded wall through which opening said support extends, said fastening device being adapted to engage a second member, to prevent movement thereof in one direction, supplemental fastening means associated with said fastening device and provided with an opening therein having a rounded wall and means for actuating said fastening device whereby the sharp edge of said support will engage the rounded wall of the opening in said fastening means.
2. In a device of the character described, a support provided with a sharp edge, fastening means provided with an opening therein having a rounded wall through which opening said support extends, said fastening means being adapted to be turned or swivelled on said support and being also adapted to engage a second member to prevent movement thereof in one direction, supplemental fastening means carried by said fastening means and also provided with an opening having a rounded wall through which opening said support extends and means for clamping said fastening means against said support whereby the sharp edge thereof will engage and be clamped against
3. In a device of the character described, a plate secured to a member, a fastening device for engaging a second member to prevent movement thereof in one direction and provided with an opening therein, a rod mounted on said plate and extending through said opening, a bolt extending through said fastening device, supplemental fastening means carried by said bolt and provided with an opening through which said rod extends and means for actuating said bolt to force said fastening means and supplemental fastening means in opposite directions and into clamped position against said rod.
4. In a device of the character described, a rod secured to a member, a fastening device slidable on said rod and adapted to engage a second member to prevent movement thereof in one direction, said fastening device being also adapted to be partially rotated on said rod, a bolt extending through said fastening device, supplemental fastening means carried by said fastening device and engaging said rod and means for rotating said bolt whereby said fastening device will be clamped against said rod in one direction and said supplemental fastening means will be clamped against said rod in a reverse direction.
5. In a device of the character described, a plate secured to a member, a rod carried by said plate, a fastening device slidable on said rod and adapted to engage a second member and prevent movement thereof in one direction and also adapted to be partially rotated on said rod, a bolt extending through said fastening device, a supplemental fastening device adapted to engage said rod and means on said bolt for clamping said fastening device against said rod in one direction and said supplemental fastening device against said rod in another direction, said plate acting to limit the degree of rotation of said fastening device on said rod.
6. In a device of the character described, a support mounted on a member, a fastening device adapted to be turned on said support, a supplemental fastening device associated with said first-named fastening device, means whereby both of said fastening devices will be moved simultaneously against said support in opposite directions and clamped thereto and a spring engaging one of said locking devices and said support.
7. In a device of the character described, a support carried by a member, a fastening device associated with said support and adapted to engage a second member to pre-

the rounded wall of said opening in said fastening means and whereby the edge thereof will also engage and be clamped against the rounded wall in the opening in said supplemental fastening means.

70

75

3. In a device of the character described, a plate secured to a member, a fastening device for engaging a second member to prevent movement thereof in one direction and provided with an opening therein, a rod mounted on said plate and extending through said opening, a bolt extending through said fastening device, supplemental fastening means carried by said bolt and provided with an opening through which said rod extends and means for actuating said bolt to force said fastening means and supplemental fastening means in opposite directions and into clamped position against said rod.

80

85

90

4. In a device of the character described, a rod secured to a member, a fastening device slidable on said rod and adapted to engage a second member to prevent movement thereof in one direction, said fastening device being also adapted to be partially rotated on said rod, a bolt extending through said fastening device, supplemental fastening means carried by said fastening device and engaging said rod and means for rotating said bolt whereby said fastening device will be clamped against said rod in one direction and said supplemental fastening means will be clamped against said rod in a reverse direction.

95

100

105

5. In a device of the character described, a plate secured to a member, a rod carried by said plate, a fastening device slidable on said rod and adapted to engage a second member and prevent movement thereof in one direction and also adapted to be partially rotated on said rod, a bolt extending through said fastening device, a supplemental fastening device adapted to engage said rod and means on said bolt for clamping said fastening device against said rod in one direction and said supplemental fastening device against said rod in another direction, said plate acting to limit the degree of rotation of said fastening device on said rod.

110

115

120

6. In a device of the character described, a support mounted on a member, a fastening device adapted to be turned on said support, a supplemental fastening device associated with said first-named fastening device, means whereby both of said fastening devices will be moved simultaneously against said support in opposite directions and clamped thereto and a spring engaging one of said locking devices and said support.

125

7. In a device of the character described, a support carried by a member, a fastening device associated with said support and adapted to engage a second member to pre-

130

vent movement thereof in one direction, said fastening device comprising two movable parts one of which clamps against said support in one direction and a supplemental part which clamps against the support in a different direction and means for actuating one of said parts.

8. In a device of the character described, a support carried by a member, a movable fastening device associated with said support and adapted to engage a second member to prevent movement thereof in one direction, an actuator for clamping a part of said fastening device against said support 15 and a supplemental movable part associated with said fastening device for clamping the

same against said support in a different direction upon movement of said actuator.

9. In a device of the character described, a rod carried by a member, a fastening device comprising two movable parts slideable on said rod and adapted to engage a second member to prevent movement thereof in one direction and means for clamping one of said parts against said rod in one direction and the other of said parts against said rod in a reverse direction.

Signed at New York in the county of New York and State of New York this 3rd day of Sept., A. D. 1924.

SAMUEL SEGAL.
